EVAPORATING PROCESS AND APPARATUS

James Mair and Guy E. Sanford, Birmingham, Ala., assignors to Goslin-Birmingham Manufacturing Company, a corporation of Alabama

Application March 12, 1953, Serial No. 341,992

4 Claims. (Cl. 159—20)

Our invention relates to an evaporating process and apparatus therefor, and particularly to the evaporation of liquids containing a considerable proportion of dissolved scale forming solids and has for an object the provision of a process and apparatus in which the heat transfer between the heating medium and the liquid being evaporated is carried out under conditions in which a minimum of scale is formed.

Another object of our invention is to provide evaporating apparatus in which the liquor being evaporated is heated under pressure at a temperature lower than that at which ebullition occurs and is conveyed to a vapor head maintained at a lower pressure and temperature where the liquor flashes into vapor to the extent required to provide an equilibrium between the vapor and liquor.

A further object of our invention is to provide a process and apparatus for the evaporation of scale forming liquids in which solids settling out of the solution being evaporated are periodically removed from the surfaces of the evaporator without interruption of the operation or disturbing the equilibrium conditions in the evaporator.

A still further object of our invention is to provide apparatus for the evaporation of liquors in which means are provided for heating the liquors under pressure in one part of the evaporator remote from the vapor head in which vaporization takes place, and in which a cleaning liquor is circulated through other parts of the evaporator, together with means to alternate the flow of liquor being evaporated and of cleaning liquor through the evaporator.

Briefly our invention comprises a heating element which may be of conventional design and which is divided into sections or compartments through which liquor may be circulated selectively through fewer than all the compartments and in which a cleaning liquor is circulated through the other compartments. Suitable steam or vapor connections are provided whereby to heat the liquor being circulated. The heating element is provided with suitable piping and valves whereby the circulation of liquor to be evaporated and cleaning liquor is alternated. Any solids precipitated out of the liquor being heated are thus promptly removed. As soon as the concentration of solids in the cleaning liquor approaches that in the liquor being evaporated the cleaning liquor is added to the feed liquor. Thus, there is no loss of solids by reason of the use of the cleaning liquor.

Another important feature of our invention resides in the provision of a vapor head separate from the evaporator and in the maintenance of a pressure and temperature of the liquor in the heating element higher than in the vapor head and at such pressure and temperature that ebullition does not occur in the heating element but in the vapor head. We thus provide a heating element in which the heating surfaces are at all times submerged and in which the liquor and cleaning fluid are at all times under pressure such as to prevent ebullition. Thus, such solids as calcium sulphate which may be forced out of the solution while being heated do not come in direct

2

contact with the heating surfaces of the heating element to become dehydrated and form hard scale. Suitable pipe connections and valve means are provided whereby the flow of cleaning fluid and liquor to be evaporated is alternated through the compartments of the heating element and the heated liquor is conveyed to the vapor head. The vapor formed in the vapor head passes to the next effect or to the condenser as is well understood.

Apparatus embodying features of our invention is illustrated in the accompanying drawings forming a part of this application in which:

Fig. 1 is a diagrammatic view illustrating the application of our invention to a multiple effect evaporator;

Fig. 2 is a longitudinal sectional view of one form of evaporator which may be employed with our invention;

Fig. 3 is a longitudinal sectional view of the opposite end thereof;

Fig. 4 is a transverse sectional view taken along the line IV—IV of Fig. 3; and,

Fig. 5 is an end view looking in the direction of the arrows V—V in Fig. 3.

Referring to the drawings for a better understanding of our invention, we show in Fig. 1 an evaporating system embodying by way of example three effects indicated generally at A, B, and C. Liquor to be evaporated

and heating medium is caused to pass from one effect to the other in the manner to be described later. Each of the effects comprises a heating element 10, and a vapor head 11, remote from the heating element and disposed at a higher level, whereby to maintain therein a lower pressure and temperature. As will later appear, the tubes of the heating element 10 are at all times submerged in liquor and ebullition takes place only in the vapor head 11. Also associated with each of the heating elements 10 is a tank 12 for cleaning liquid which is circulated, in a manner to be described, through the heating element to remove deposits of solid matter precipitated out of the liquor being heated in the heating element.

Referring now to Figs. 2 to 5 inclusive we show by way of example a heating element which may be employed with our invention, though it will be apparent to those skilled in the art that many types of heating elements may be used, and others will suggest themselves to those skilled in the art which might better meet their requirements.

As shown in Figs. 2 to 5 inclusive, each heating element comprises an outer shell 13 having tube sheets 14 and 16 therein through which tubes 17 extend and are secured in place in the usual manner. The tube sheets 14 and 16 are spaced respectively from the heads 18 and 19 of the heating element. The space defined between the head 19 and the tube sheet 16 is divided by diametral walls 21 and 22 into four compartments 23, 24, 25 and 26. The space between the head 18 and the tube sheet 14 is divided by a vertically extending diametral wall 27 into two chambers. Pipe connections 28 and 29 afford communication with the chambers 23 and 24, and pipe connections 31 and 32 afford communication with the chambers 25 and 26. It will be seen that by reason of the compartments just described, liquor admitted into the heating element through the pipe connection 31 passes through chamber 25 to the opposite end of the heating element and is returned to chamber 26 and out through pipe connection 32. Also, liquor admitted through the pipe connection 28 enters the chamber 23 and passes to the opposite end of the heating element and is returned to the chamber 24 and out through the pipe connection 29. A heating medium such as steam, or vapor, is admitted to the casing through a pipe connection 35 and condensate is removed through a pipe connection 34.

While forward flow, backward flow, or mixed forward and backward flow as is practiced in other evaporating

systems, may be employed with our invention, we show for the purpose of illustration, and by way of example only, a forward flow system. The liquor to be evaporated is introduced through a valved pipe connection 36 and passes through a forced circulation pump 37 selectively, to the pipe connections 28 and 31. Valves 38 and 39 provide means whereby the flow may be diverted selectively to either of said pipe connections. The liquid is heated in the heating element 10 and is returned through the pipe connections 29 or 32 as the case may be. The pipes 29 and 32 connect to a pipe 33 which leads upwardly to the vapor head 11. Valves 41 and 42 in the pipes 29 and 32 provide means whereby the liquid may be directed, selectively, from the compartments of the heating element 10 to the vapor head 11.

The tank 12 may contain water, initially, or a solution effective to dissolve and remove solids deposited in the heating element 10. The tank 12 is preferably located, as shown, at a level above that of the heating element. Connected to the tank 12 is an outlet pipe 43 which leads to the inlet side of a forced circulation pump 44 which discharges through a pipe 46 and through pipes 47 and 48 which connect respectively with the inlet pipe connections 28 and 31 of the heating element 10. Valves 49 and 51 provide means whereby the cleaning liquid may be passed alternately and selectively through the pipes 28 and 31. Return pipes 52 and 53 are connected, respectively, to the return pipes 29 and 32 from the heating element 10, and are provided respectively with valves 54 and 56 whereby cleaning liquid may be returned selectively to the tank 12.

It will be seen that by closing the valve 38 and opening the valve 49 and closing the valve 41 and opening the valve 56, that cleaning liquid may be forced into the heating element 10 through the pipe connection 28 and out through the pipe connection 29 and returned to the tank 12. Also, by closing the valve 39 and opening the valve 51 and closing the valve 42 and opening the valve 54, cleaning liquid can be forced through the other compartments of the heating element 10. In accordance with our invention, it is contemplated that the valves described will be opened and closed periodically and alternately, to provide first for the circulation of the liquor being heated through one side of the heating element while cleaning liquid is being circulated through the other. It is also contemplated that the valves described may be operated by any timed mechanical means known in the art to alternate the flow of liquor and cleaning liquid, but which forms no part of our invention.

The liquor after being heated passes selectively from the separate compartments of the heating element upwardly to the vapor head 11. In the carrying out of our improved process, it is contemplated that the liquor shall be heated in the heating elements of the separate effects to temperatures just short of that at which ebullition occurs at the pressure prevailing in the heating element. The pressure is maintained in the separate heating elements by means of the forced circulating pumps 37 and by reason of the fact that the vapor heads 11 are disposed at a higher level than the heating elements. Accordingly, when the heated liquor passes upwardly into the vapor head, a portion flashes into vapor and the remainder passes downwardly through a pipe 57 to which the liquor feed 36 is connected and which leads to the inlet side of the pump 37. Vapor formed in the vapor head 11 passes through a pipe 58 to the heating element 10 of effect B. At 59 we show a pipe which is connected to the pipe 33 for conveying heated liquor to the vapor head and which is controlled by means of a valve 61. When the liquor has reached the required concentration, it is contemplated that it will pass through the valve 61 and pipe 59 to the pipe 57 of the effect B thereby providing for the liquor feed to that effect. The operation of the effects B and C are the same as described for effect A except that the vapor formed in the vapor head 11 of the effect C passes to a

condenser 62. The finally concentrated liquor may be discharged through a valve 63 at the lower end of the pipe 33 in effect C.

From the foregoing it will be apparent that we have provided a process and apparatus for the evaporation of scale forming liquids in which the liquids are heated in a zone remote from and at a higher pressure than that in which ebullition occurs, whereby solids settling out of the solution being evaporated do not come in direct contact with the heating elements of the evaporator so that they become dehydrated and form a hard scale, but are carried in suspension in the liquid. Furthermore, it will appear that the alternate and periodical circulation of a hot cleaning solution through the compartments of the heating element will remove solid matter settling out of the solution in the heating element. It is contemplated by our invention that when the concentration of solids in the cleaning solution approaches that, or approximates that of the liquor feed, that, instead of returning the cleaning solution to the tank 12, it will be added to the liquor feed, for example, by opening the valve 41 or 42, as the case may be, instead of returning the solution to the tank 12. Additional cleaning solution may be added to the tank 12 through a pipe connection 64.

While we have shown our invention in but one form, it will be obvious to those skilled in the art that it is not so limited, but is susceptible of various changes and modifications without departing from the spirit thereof, and we desire, therefore, that only such limitations shall be placed thereupon as are specifically set forth in the appended claims.

What we claim is:

1. The method of evaporating liquid which comprises maintaining a closed system circulating supply of cleaning liquid separate from the liquid to be evaporated, passing liquid to be evaporated and the cleaning liquid simultaneously in separate parallel paths through one zone in heat transfer relation with a heating medium therein maintained in a path separate from both the liquid to be evaporated and the cleaning liquid and heating the liquid to be evaporated therein under pressure to a temperature just below that at which ebullition occurs, regularly interchanging the liquid whereby after interchange each liquid flows in the path formerly occupied by the other liquid before interchange, conveying the heated liquid to be evaporated to another zone remote from the heating medium which zone is maintained at a pressure below that at which ebullition occurs in the heated liquid, and recirculating the cleaning liquid in the said closed system.

2. In an evaporator system including a heating element having a plurality of compartments, means for passing liquor to be evaporated in indirect heat transfer relation with heating vapor selectively through some of the compartments, means to maintain the liquor under pressure sufficient to prevent its ebullition in the heating element, means to circulate cleaning liquid simultaneously and selectively through others of said compartments separate from both the liquor being evaporated and the heating vapor, and a vapor head separate from the heating element disposed to provide for the ebullition of the liquor therein and the separation of vapor from the liquor.

3. In an evaporating assembly, a heating element having a chamber at each end divided into compartments with tubes connecting the compartments for the circulation of liquid therethrough in indirect heat transfer relation with a heating medium, means to circulate a liquid to be evaporated through some of the compartments and tubes associated therewith, means to circulate a cleaning liquid simultaneously through the other compartments and tubes associated therewith separate from both the liquid to be evaporated and the heating medium, valve means for interchanging the flow of liquid to be evaporated and cleaning liquid through said compartments, a vapor head remote from said heating element, and means

for passing liquid to be evaporated from the heating element to said vapor head.

4. In an evaporating assembly, a heating element having a chamber at each end divided into compartments and with tubes connecting the compartments for the circulation of liquid therethrough in indirect heat transfer relation with a heating medium, means to circulate a liquid to be evaporated through some of the compartments and tubes in a flow path always separate from the heating medium associated therewith, means to circulate a cleaning liquid simultaneously through the other compartments and tubes associated therewith and always separate from both the heating medium and the liquid to be evaporated, valve means for interchanging the flow of liquor to be evaporated and cleaning liquid through said compartments, a vapor head remote from said heating ele-

ment, means for passing liquor to be evaporated from the heating element to said vapor head, said vapor head being disposed to provide for flashing a part of the liquor to be evaporated whereby to maintain a lower pressure in the vapor head than in the heating element.
